BOWLING BALL RACK OR SIMILAR ARTICLE

Richard G. Reineman, Muskegon, Mich., assignor to The Brunswick-Balke-Collender Company, a corporation of Delaware

Application January 10, 1955, Serial No. 33,914

Term of patent 14 years

(Cl. D34—5)

Fig. 1 is a top plan view of a bowling ball rack or similar article, showing my new design;

Fig. 2 is a side elevation thereof;

Fig. 3 is an end view thereof, taken from the left end of Fig. 2; and

Fig. 4 is an end view thereof, taken from the right end of Fig. 2.

The dominant features of my new design are shown in solid lines in the drawing.

I claim:

The ornamental design for a bowling ball rack or similar article, as shown and described.
